ATTORNEY'S

UNITED STATES PATENT OFFICE.

JOSEPH CONNER, OF NEW YORK, N. Y., ASSIGNOR TO THE FIRM OF JOHN MATTHEWS, OF SAME PLACE.

BOTTLE-STOPPER.

SPECIFICATION forming part of Letters Patent No. 351,496, dated October 26, 1886.

Application filed March 13, 1886. Serial No. 195,060. (No model.)

To all whom it may concern:

Be it known that I, JOSEPH CONNER, of the city, county, and State of New York, have invented an Improvement in Bottle-Stoppers, of which the following is a complete specification, reference being had to the accompanying drawings, in which—

Figures 1 and 2 represent sectional side views of bottle-stoppers of well-known construction, to which my invention is intended to be applied. Figs. 3 and 4 represent similar views of my improved stoppers.

The object of this invention is to provide certain internal bottle-stoppers—that is to say, stoppers which are intended to close upwardly with an elastic peripheral flange against the seat in the throat of the bottle—with a packing which shall at all times hug the stem of the stopper.

The old kind of stoppers, which I seek to improve, is represented in Figs. 1 and 2 of the drawings, and consists of a rigid stem, A, and a rubber or other flexible packing, B, which packing is slipped upon the lower end of the stem, so as to tightly embrace and surround the same. The packing B has an outwardly-projecting flexible flange, a, which seats against the throat b of the bottle C. The difficulty with this kind of stopper is that when pressure is applied internally against the stopper the flange a will be distended or crowded outward, as is clearly shown in Fig. 2, so as to partly draw the upper portion of the packing away from the stem A and produce an annular cavity, d, around said stem. This cavity will remain open to the reception of dust, insects, and other impurities during the entire period of time the bottle is charged with gaseous liquid, and when afterward the bottle is emptied the packing B will again close on the stem and grasp and retain the impurities which settle in the said cavity or groove d. As these stoppers, when the bottle is being opened, are forced into the liquid contents

thereof, the aforesaid impurities will become 45 in part absorbed by the liquid, tainting the same. This is one of the principal difficulties connected with the use of ordinary bottle-stoppers. They serve to taint the liquid by the above-mentioned impurities and at all 50 times to retain sufficient of the impurities to be objectionable in continual use. The stoppers, being within the bottle, cannot conveniently be cleaned, especially if the impurities settle, as has been stated, in a cavity, which 55 becomes subsequently closed whenever the bottle is opened.

My invention consists in providing a packing of the kind stated, and which surrounds the lower part of the stem and carries the 60 flange a, with an upward projection, e, on the packing directly above the seat or flange portion a, so that said upwardly-projecting tubular portion e of the packing will at all times tightly hug the stem A. When pressure is 65 applied to the stopper from within and the seat or flange portion a distended, as in Fig. 4, the tubular projection e will thereby be drawn down on the stem, still tightly hugging the same, all as shown in Fig. 4. By this 70 means the objectionable open groove or cavity heretofore referred to is avoided, and all danger of contaminating the liquid with impurities that settle in the folds of the stopper obviated.

I claim—

The internal bottle-stopper consisting of the stem A and elastic packing B, which surrounds the lower end of said stem, and which has the flexible outwardly-extending peripheral flange a and the upwardly-projecting tubular portion e above said flange and around the stem, substantially as herein shown and described.

JOSEPH CONNER.
